UNITED STATES PATENT OFFICE.

LAMBTON LE BRETON MOUNT, OF BAYSWATER, LONDON, ENGLAND.

FURNACE FOR MELTING METALS, GLASS, AND THE LIKE.

988,131.

Specification of Letters Patent.

Patented Mar. 28, 1911.

Application filed August 8, 1908. Serial No. 447,596.

To all whom it may concern:

Be it known that I, LAMBTON LE BRETON MOUNT, a subject of the King of Great Britain and Ireland, residing at Bayswater, in the county of London, England, have invented Improvements in Furnaces for Melting Metals, Glass, and the Like, of which the following is a specification.

This invention relates to furnaces for melting metals, glass or the like and for roasting or calcining ores, salt cake, or the like and other purposes.

Main objects of this invention are to obtain economy of fuel by an improved arrangement and construction of the parts of such furnaces, to obtain a higher temperature with the same expenditure of fuel than is possible with the heretofore usual construction of furnaces, to provide an improved construction of recuperator comprised in such furnaces, and to provide improved means for taking up thrust due to expansion upon adjacent abutting work such as the crown of the furnace and end walls thereof.

Figure 1 of the accompanying illustrative drawings shows in longitudinal section corresponding to the line A, B of Fig. 2 one construction of glass melting tank furnace embodying this invention. Fig. 2 is a horizontal section corresponding to the line C D of Fig. 1. Fig. 3 is a half transverse section of the furnace corresponding to the line E F of Fig. 1. Fig. 4 is a transverse section of the furnace the right hand half corresponding to the line G H and the left hand half corresponding to the line I J of Fig. 1. Fig. 5 is a detail view to a larger scale showing in side elevation a portion of the recuperator wall built up of paneled tiles one of which is shown in section in Fig. 6. Fig. 7 is a detail view to a larger scale showing an end portion of the furnace crown and adjacent parts.

A glass melting furnace is only taken as an example and it will be understood that the construction and shape of the tank or basin may be altered in form according to the varying uses for which the furnace is designed.

The furnace is built on a suitable concrete base *a* immediately above which is a series of air flues *b* that prevent the bottom of the tank from getting too hot, through which the recuperator *c* is supplied with the nec-

essary air to be highly heated for the furnace. For the purpose of regulating the supply of air to the flues *b* steam jets with valves, not shown, are arranged at the entrance of the flues.

The sides *f* and the ends *g* of the tank are built in their proper places on the bottom or base *a*. *i* is a passage through which air can pass in order to keep cool and preserve the inner end *g* when it becomes thin through wear. Above the side blocks *f* and under the spring of the crown *h* of the furnace proper are built the side walls *k* with the necessary provision for gathering holes *m* and other ports *n*.

At one side of the tank is a conduit *p* for conveniently supplying the tank with the material to be melted.

Each end of the crown *h* abuts against a series of flat tiles *q* and *t* built on the gable ends *r* of the furnace to the same thickness and contour as the crown. These courses of flat tiles *q* and *t* are so laid, side by side, on the gable as to provide spaces *s* between their inner ends, tiles *u* covering the spaces otherwise left between the adjacent ends of the tiles *q* and *t*.

To prevent the tiles fusing together or sticking, sand or other suitable material is spread between the courses of the tiles thereby enabling them to yield easily to the expansion of the crown *h* which partially diminishes the spaces *s* between the tiles *q* and *t* without unsealing the work and without in any way disturbing or deranging the adjacent brickwork and recuperator. Should the furnace cool, the consequent shrinkage is taken up by adjustment of the usual longitudinal tie bracing as well understood, and on re-heating and re-expansion taking place, the tie bracing is eased accordingly, the structural work remaining at all times undisturbed.

At a suitable height above the crown *h* and of the same contour another crown 1 is built so as to leave a part annular space 2 that forms a passage for the highly heated air which before being heated enters the recuperator at 4 and leaves it at 5. From the passage 2 the hot air flows through crown 105 ports 6 into the combustion chamber 7.

At a suitable height above the second crown 1 is built a third crown 8 so as to form a second annular passage 10 for the waste gases which enter the recuperator 110

from the furnace through passages 11 and leave it at 12 whence they flow along the top of the recuperator to vertically ascending ports 13 into the annular passage 10 to 5 the down flues 14 and thence to a ground flue 15 to be further utilized if necessary and thence to a chimney, not shown.

The recuperator *e* is built contiguous to the inner end of the tank on a supporting 10 arch 16. It consists of a series of vertical flues 17 through which the hot waste gases pass horizontally and impart heat to the walls 18. The walls 18 separating the flues 17 are hollow and inside them the whole of 15 the air necessary for the combustion of the gas supplied by the pipe 20 travels the opposite or reverse way to the hot waste gases, acquiring in its course the major portion of the heat from the walls. The 20 walls 18 are built of angular tiles 22, Figs. 5 and 6, of material which is highly refractory and not liable to expand much when heated, such tiles being laid diagonally in oblique courses, so as to keep their joints 25 closed by gravity while enabling them to slide one upon the other in an upward direction, see Fig. 5. The walls 19 against which the ends of the hollow walls 18 of the recuperator abut are substantial walls 30 formed of wedge shaped bricks, and to resist upward thrust due to expansion of the recuperator the upper part of each such wall is formed as an inverted arch 21, see 35 Figs. 3 and 4, external ties of usual form being provided. The tiles 22 are paneled, thus reducing their thickness without reducing the area of their bearing faces. The thinness of the panels facilitates the transmission of heat from the hot waste gases to 40 the passing air. The bearing faces of each tile are formed with grooves to receive suitable material whereby the joints are more effectually sealed.

From the recuperator the highly heated 45 air travels along the top of the crown *h* of the furnace, within the part-annular passage 2 formed by the second crown 1, to the place of combustion thereby increasing the temperature of combustion to a great degree. 50 This increased temperature in turn increases the heat of the furnace and of the recuperator, which further increases the heat of the air traveling therein, and of the flame; the action being automatically self-augmenting, and giving very high economical 55 results.

The foregoing satisfactory results are further assisted by the fact that the highly heated air from the recuperator does not lose heat by radiation on its way to the fire as it travels on the top of the heated crown of the furnace, and is covered by the waste heat part-annular passage 10. Also heat is not lost by radiation from the crown proper, 60 as in other furnaces, because it is protected 65

by the highly heated air traveling thereon within the first part-annular passage 2.

It has heretofore been proposed to construct a dome-topped furnace with three superimposed crowns between which air and products of combustion are led; rectangular tank furnaces have also been proposed with three superimposed crowns between which flues of less width than the crowns are formed for the circulation of air and products of combustion. As far as I am aware in all these constructions comparatively cool air for supporting combustion has been led through the lower passages, that is to say those nearest the combustion chamber; 70 this arrangement tends to cool the furnace chamber, whereas in the improved furnace the air is highly heated before passing into the lower crown passages and so tends to increase the temperature in the furnace 75 chamber as hereinbefore described.

Hitherto the only partially successful attempts to thoroughly utilize the simple action of reverse currents of recuperation, is clearly attributable to the expansion by heat, 80 thrusting and warping the work, and opening the joints between the bricks, or cracking the same, with the consequent mingling of the currents and thwarting of the objects desired. 85

The above disadvantages are avoided by the hereinbefore described improved method of arranging the tiles in the recuperator, which seal the joints by gravity.

What I claim is:—

1. In a furnace, the arrangement between abutting parts thereof that move relatively upon expansion and contraction, of tiles adapted to slide one over the other without disturbing the furnace parts when expansion occurs and means to prevent said tiles sticking. 105

2. In a furnace, a tank or chamber, a crown or top to said tank or chamber, end walls, tiles, between said end walls and said crown or top, arranged to slide one over the other without disturbing the furnace parts when expansion occurs. 110

3. In a furnace, a tank or chamber, a crown or top to said tank or chamber, end walls, tiles, between said end walls and said crown or top, arranged to slide one over the other without disturbing the furnace parts when expansion occurs, and means to prevent said tiles sticking. 115

4. In a furnace, a tank or chamber, a recuperator, means for admitting cool air to said recuperator, conduits through which hot gases from said tank or chamber pass to said recuperator, a crown over said tank or chamber formed with two part annular passages of approximately the full width thereof arranged one over the other, conduits through which gases from said recuperator flow to the outer of the two pas- 125 130

sages of said crown, an exit flue for spent gases, conduits between the outer of the two passages of said crown and said flue, conduits through which heated air is led from 5 said recuperator to the inner of the two passages of said crown, and conduits through which heated air from the inner of the two passages of said crown flows to said tank or chamber.

10 5. In a furnace, a tank or chamber, a recuperator means for admitting cool air to said recuperator, conduits through which hot gases from said tank or chamber pass to said recuperator, a crown over said tank
15 or chamber formed with two part annular passages of approximately the full width thereof arranged one over the other, tiles against which the ends of said crown are laid in courses side by side with spaces between their adjacent ends, other tiles covering the spaces between the adjacent ends of said tiles, means to prevent all said tiles sticking, conduits through which gases from said recuperator flow to the outer of the two
20 25 passages of said crown, an exit flue for spent gases, conduits between the outer of the two passages of said crown and said flue, conduits through which heated air is led from said recuperator to the inner of the two passages of said crown, and conduits through which heated air from the inner of the two passages of said crown flows to said tank or chamber.

6. In a furnace, a tank or chamber, a recuperator, means for admitting cool air to said recuperator, conduits through which hot gases from said tank or chamber pass to said recuperator, a crown over said tank or chamber formed with two part annular passages of approximately the full width thereof arranged one over the other, tiles against which the ends of said crown abut and are laid in courses side by side with spaces between their adjacent ends, other tiles covering the spaces between the adjacent ends of said tiles, means to prevent all said tiles sticking, bracing for adjustment in accordance with expansion and contraction, conduits through which gases from said recuperator flow to the outer of the two passages of said crown, an exit flue for spent gases, conduits between the outer of the two passages of said crown and said flue, conduits through which heated air is led from said recuperator to the inner of the two passages of said crown, and conduits through which heated air from the inner of the two passages of said crown flows to said tank or chamber.

60 7. In a furnace, a recuperator the walls
of which are built of tiles placed diagonally
in oblique courses, said tiles being capable of
sliding one upon the other, means for ad-
mitting cool air to said recuperator, conduits
through which hot gases from said tank or
65 chamber pass to said recuperator, a crown

over said tank or chamber formed with two part annular passages of approximately the full width thereof arranged one over the other, conduits through which gases from said recuperator flow to the outer of the two 70 passages of said crown, an exit flue for spent gases, conduits between the outer of the two passages of said crown and said flue, conduits through which heated air is led from said recuperator to the inner of the 75 two passages of said crown, and conduits through which heated air from the inner of the two passages of said crown flows to said tank or chamber.

8. In a furnace, a recuperator the walls of which are built of tiles placed diagonally in oblique courses, said tiles being capable of sliding one upon the other, means for admitting cool air to said recuperator, conduits through which hot gases from said tank or chamber pass to said recuperator, a crown over said tank or chamber formed with two part annular passages of approximately the full width thereof arranged one over the other, tiles against which the ends of said crown abut laid in courses side by side with spaces between their adjacent ends, other tiles covering the spaces between the adjacent ends of said tiles, means to prevent all said tiles sticking, conduits through which gases from said recuperator flow to the outer of the two passages of said crown, an exit flue for spent gases, conduits between the outer of the two passages of said crown and said flue, conduits through which heated air is led from said recuperator to the inner of the two passages of said crown, and conduits through which heated air from the inner of the two passages of said crown flows to said tank or chamber.

9. In a furnace, a recuperator the walls of which are built of tiles placed diagonally in oblique courses, said tiles being capable of sliding one upon the other, means for admitting cool air to said recuperator, conduits through which hot gases from said tank or chamber pass to said recuperator, a crown over said tank or chamber formed with two part annular passages of approximately the full width thereof arranged one over the other, tiles against which the ends of said crown abut laid in courses side by side with spaces between their adjacent ends, other tiles covering the spaces between the adjacent ends of said tiles, means to prevent all said tiles sticking, bracing for adjustment in accordance with expansion and contraction, conduits through which gases from said recuperator flow to the outer of the two passages of said crown, an exit flue for spent gases, conduits between the outer of the two passages of said crown and said flue, conduits through which heated air is led from said recuperator to the inner of the two passages of said crown, and conduits 130

through which heated air from the inner of the two passages of said crown flows to said tank or chamber.

10. In a furnace, a tank or chamber, a recuperator in line with said tank or chamber the walls of which are built of tiles placed diagonally in oblique courses, said tiles being capable of sliding one upon the other, conduits below said tank or chamber for cool air flowing to said recuperator, a conduit above said tank or crown, adapted to lead hot air from said recuperator to said tank or chamber, a combustible gas supply conduit to said tank or chamber, an exit flue, a conduit above said hot air conduit adapted to lead the heating gases from said recuperator to said exit flue, and passages for hot gases connecting said tank or furnace to said recuperator.
- 15 11. In a furnace, a tank or chamber, a recuperator in line with said tank or chamber the walls of which are built of tiles placed diagonally in oblique courses, said tiles being capable of sliding one upon the other, end walls supporting the recuperator walls built of wedge shaped bricks, inverted arches and cross ties adapted to retain said end walls in position, conduits below said tank or chamber for cool air flowing to said recuperator, a conduit above said tank or crown adapted to lead hot air from said recuperator to said tank or chamber, a combustible gas supply conduit to said tank or chamber, an exit flue, a conduit above said hot air conduit adapted to lead the heating gases from said recuperator to said exit flue, and passages for hot gases connecting said tank or furnace to said recuperator.
- 20 12. In a furnace, a tank or chamber, a recuperator in line with said tank or chamber the walls of which are built of tiles placed diagonally in oblique courses, said tiles being capable of sliding one upon the other, end walls supporting the recuperator walls built of wedge shaped bricks, means adapted to retain said walls in position, conduits below said tank or chamber for cool air flowing to said recuperator, a conduit above said tank or crown adapted to lead hot air from said recuperator to said tank or chamber, a combustible gas supply conduit to said tank or chamber, an exit flue, a conduit above said hot air conduit adapted to lead the heating gases from said recuperator to said exit flue, and passages for hot gases connecting said tank or furnace to said recuperator.

35 duct to said tank or chamber, an exit flue, a conduit above said hot air conduit adapted to lead the heating gases from said recuperator to said exit flue, and passages for hot gases connecting said tank or furnace to said recuperator.

40 12. In a furnace, a tank or chamber, a recuperator in line with said tank or chamber the walls of which are built of tiles placed diagonally in oblique courses, said tiles being capable of sliding one upon the other, end walls supporting the recuperator walls built of wedge shaped bricks, inverted arches and cross ties adapted to retain said end walls in position, conduits below said tank or chamber for cool air flowing to said recuperator, a conduit above said tank or crown adapted to lead hot air from said recuperator to said tank or chamber, a combustible gas supply conduit to said tank or chamber, an exit flue, a conduit above said hot air conduit adapted to lead the heating gases from said recuperator to said exit flue, and passages for hot gases connecting said tank or furnace to said recuperator.

45 Signed at London England this 28th day of July 1908.

LAMBTON LE BRETON MOUNT.
